UNITED STATES PATENT OFFICE.

MARCUS W. WILLIAMS, OF ATLANTA, GEORGIA.

AXLE-ARM ADJUSTER.

1,172,332.

Specification of Letters Patent. Patented Feb. 22, 1916.

Application filed September 25, 1914. Serial No. 863,481.

To all whom it may concern:

Be it known that I, MARCUS W. WILLIAMS, a citizen of the United States, residing at Atlanta, in the county of Fulton and State of Georgia, have invented certain new and useful Improvements in Axle-Arm Adjusters; and I do hereby declare the following to be a full, clear, and exact description of the invention, such as will enable others skilled in the art to which it appertains to make and use the same.

My invention relates to special tools, more especially to bending tools, and has for an object the production of novel, inexpensive and efficient means for bending, straightening or setting axle-arms for vehicles.

As a further object the present invention contemplates the production of improved means for alining axle-arms for vehicles without either the application of heat, the necessity of removing the axle from the running gear, or placing the vehicle in a shop with a consequent loss of time. The invention may therefore be herein termed a cold axle setter or axle-arm adjuster.

The present improvements will be herein-after particularly described and pointed out in the claims following.

In the accompanying drawings which form part of this application for Letters Patent, and whereon corresponding numerals indicate like parts in the several views: Figure 1 is a side elevation of my invention applied to a vehicle axle and axle-arm in process of straightening; Fig. 2 is an end view of parts illustrated by Fig. 1; Fig. 3 is a view in perspective of the body member of my invention detached, and Fig. 4 is also a detached perspective view showing a tension yoke used to transmit to axle-arms a bending strain as may be required.

Reference being had to the drawings and numerals thereon, 1 indicates the body member of my improved axle-arm adjuster, preferably formed of wrought iron or steel, and of liberal dimensions as shown for purposes of strength. Integral with or permanently secured to the innermost end of body member 1 is an annulus 2 arranged at right angles to the longitudinal axis of the adjuster, and for purposes which will later appear.

Mounted upon the body member 1, which it surrounds as best shown by Fig. 2, is a depending yoke 3 also of substantial dimensions and material, having closed ends 4, 5

and sides 6, 6 as shown by Fig. 4. The lowermost of these ends 5 is curved at 7 to afford a suitable seat for an axle-arm when the adjuster is in service, the upper end 4 being thickened by a surface boss 8 and tapped at 8' to receive an operating screw 9 adapted thus to bear upon the upper surface of body member 1 when the axle adjuster is in service. In like manner the said body member 1, is perforated adjacent to its opposite or inner end by a threaded aperture 10 provided with a set screw 11, the use of which will now appear in combination with a brief description of operation.

For purposes of this description, let A indicate an ordinary vehicle axle, B the usual bed-iron secured to said axle by a saddle clip a, and C an axle-arm projecting from B slightly out of alinement. If now by accident or otherwise an axle-arm C is bent out of true alinement more or less, for example as shown slightly bent downward by Fig. 1, my improved axle-arm adjuster may be thereupon applied, as shown by Fig. 1, with its annulus 2 surrounding axle A, and its set screw 11 bearing upon the upper surface of said arm at its inner end. Power applied to operating screw 9 by means of an ordinary wrench (not shown) now produces an upward pull upon yoke 3 resting beneath the outer end of the axle-arm C until the latter has been straightened. In like manner the adjuster may readily be rotated to a position immediately below axle-arm C for the purpose of bending same downward if occasion requires, or to any intermediate position for operating similarly in any direction, and it will be noted that the extent to which an axle-arm may thus be bent depends mainly upon the length of yoke 3.

Having thus described my invention in one form of embodiment, the most practical form at present known to me, it should be understood that I do not confine myself to this, but claim all such modifications thereof as may be capable of accomplishing substantially the same results by substantially the same means.

Having thus described my invention what I now claim and desire to secure by Letters Patent is:

1. In an axle arm adjuster, the combination of a body member rotatable upon a vehicle-axle, an engaging loop provided on one end of said body portion, a set screw ar-

ranged in close proximity to the said loop and adapted to pass through the said body portion and engage axle arm, a yoke arranged to pass over the other end of the body portion and engage the end of the said axle arm upon a side opposite to that of the said set screw, and means including a set screw arranged to pass through the said yoke and bear upon the upper surface 10 of the body portion.

2. In an axle arm adjuster the combination of a body member comprising a bar rotatably mounted upon a vehicle-axle, an integrally formed engaging ring provided on one end of the said bar, a set screw arranged in close proximity to the said ring adapted to pass through the said bar and bear upon the axle arm, a removable yoke arranged to pass over the other end of the 15 bar and engage the outer end of the said axle arm upon a side opposite to that of the said screw, and means including a set screw arranged to pass through one end of the said yoke and bear upon the said bar.

3. In an axle arm spindle adjuster, the combination of a body member comprising a non-yielding bar adapted to be rotatably mounted with relation to the spindle por-

tion of a vehicle-axle and arranged to extend parallel with and for a distance substantially equal to the length of the said axle spindle, an integrally formed engaging ring provided on the innermost end of the said non-yielding bar at right angles thereto and adapted to encircle and engage 35 the vehicle axle without engaging the spindle thereof, a set screw arranged in close proximity to the said ring and adapted to pass through the said non-yielding bar and bear upon the vehicle axle spindle, an adjustable yoke arranged to pass over the outer end of the said bar and engage the outer end of the vehicle axle spindle upon a side opposite that engaged by the aforesaid screw, and means for flexing the vehicle axle spindle, including a set screw arranged to pass through one end of said yoke and bear upon the upper surface of the said non-yielding bar.

In testimony whereof I affix my signature, in presence of two subscribing witnesses.

MARCUS W. WILLIAMS.
